UNITED STATES PATENT OFFICE.

GEORGE HORATIO JONES, OF LONDON, ENGLAND.

FOUNTAIN-PEN.

SPECIFICATION forming part of Letters Patent No. 445,317, dated January 27, 1891.

Application filed May 28, 1889. Serial No. 312,378. (No model.) Patented in England May 16, 1888, No. 7,293.

To all whom it may concern:

Be it known that I, GEORGE HORATIO JONES, a subject of the Queen of Great Britain and Ireland, residing at 57 Great Russell Street, London, England, have invented certain new and useful Improvements in Reservoir or Fountain Pens, (patented in England May 16, 1888, No. 7,293;) and I do hereby declare the following to be a full, clear, and exact description of the invention, such as will enable others skilled in the art to which it appertains to make and use the same.

The object of my invention is to provide a reservoir or fountain pen of extremely simple construction which can be manufactured at a lower cost than those hitherto constructed.

In the accompanying drawings I have shown how my said invention can be conveniently and advantageously carried into practice.

Figure 1 is a vertical longitudinal central section showing one form of pen constructed according to my said invention. Figs. 2 and 3 are vertical longitudinal central sections showing various modifications, hereinafter described.

Like letters indicate corresponding parts throughout the drawings.

A is a tube, formed of glass, metal, or other suitable material, the upper extremity of which may be open and provided with a rim or flange B. The lower extremity of the said tube A is tapered, so as to form a nozzle A', bent in toward the nib of the pen and having a small hole C in the extremity of the same. I prefer to form the above-described tube of the same or nearly the same diameter as the handle of an ordinary pen-holder. To the lower extremity of the said tube is fitted a suitable metal or other socket D, such as is usually employed upon an ordinary pen-holder and intended to receive a nib D' of any suitable description. The said socket or holder D is placed upon the tube A in such a manner that the nozzle A' is situated in a convenient part of the nib D', so as to supply ink to the same in the manner hereinafter described. Instead of the said holder, I sometimes employ a barrel-pen of suitable dimensions.

Upon the upper extremity of the tube A, when open, is provided an elastic or flexible

piece E, formed of india-rubber or other suitable elastic material and stretched tightly over the hereinbefore-mentioned rim or flange. The elastic or flexible piece E is secured upon the tube A by means of a ring or band E', or in any other suitable manner. This elastic cap can be used to give a forward impulse to the ink when necessary. 60

To fill the tube with ink, I warm the tube slightly, so as to exhaust the air or a portion of the air from the said tube, and then insert the nozzle A' in the ink, which latter is caused to enter the tube A through the hole C by atmospheric pressure. To supply this nib D' with ink when in use, all that is necessary is to press slightly upon the elastic or flexible piece E.

In some instances, instead of the india-rubber or other material hereinbefore described, I provide the upper extremity of the tube A with a suitable removable cap having an elastic or flexible metal top, by pressing upon which the ink can be supplied to the nib D' 75 in the manner hereinabove described. In this instance the said tube may be filled with ink by removing the said cap and pouring the ink into the tube A.

Fig. 2 illustrates a modification wherein the tube A is provided with a nozzle A', curved or bent in the form shown, and provided at its extremity with a screw-threaded portion A², intended to receive a small cap J when the pen is not in use. When the pen is in use, the small cap J can be placed upon a screw-threaded projection F', provided upon the cap F. F² is a piece of india-rubber or other suitable material, against which the upper extremity of the tube A bears when 90 the said cap F is in position, thus forming a tight joint. When not required for writing purposes, the barrel-pen or holder D or nib D' can be moved upward along the tube A, and the device may then be conveniently 95 placed in the pocket with the greatest safety and security.

Fig. 3 shows still further modifications and illustrates a different position in which the hole or holes C may be placed in the nozzle 100 A' of the tube A. These modifications will be readily understood from the drawings without further description.

Although I have hereinbefore described va-

rious methods of carrying my said invention into practice, it is obvious that I can somewhat further modify the construction of my improved reservoir or fountain pen without departing from the nature of my said invention.

Having now particularly described and ascertained the nature of my said invention and in what manner the same is to be performed, I declare that what I claim is—

The combination, with the tubular ink-reservoir, perforated nozzle, and flexible cap, located at the upper end of the reservoir and

adapted to aid the flow of ink to the nib, of a screwed or otherwise securely-attachable cap 15 to cover the nozzle, and a socket formed with or adapted to receive a nib and fitted to slide on the said tubular reservoir, substantially as and for the purpose above specified.

In testimony whereof I affix my signature in 20 the presence of two witnesses.

GEORGE HORATIO JONES.
